United States Patent Office.

RUFUS S. MITCHELL AND GEORGE Z. KESSINGER, OF ELIZABETH,
INDIANA.

Letters Patent No. 90,011, dated May 11, 1869.

IMPROVED FLOUR-BOLT.

The Schedule referred to in these Letters Patent and making part of the same.

To all whom it may concern:

Be it known that we, RUFUS S. MITCHELL and GEORGE Z. KESSINGER, of Elizabeth, in the county of Harrison, and State of Indiana, have invented a new and useful Improvement in Bolts for Flouring-Mills; and we do hereby declare that the following is a full, clear, and exact description of the construction and operation of the same, reference being had to the annexed drawings, making a part of this specification.

The nature of our invention consists in stretching an elastic cord, or other flexible material, parallel and lengthwise the bolting-reel, and fastening it to springs, attached in any convenient manner to the bolting-chest, which cord, passing over the ratchet-bands, around the reel or shaft, is allowed to snap each side of the bolting-reel one or more times as it revolves, for the purpose of cleaning the bolting-cloth, and preventing beards from working into the cloth and injuring it.

We construct a bolting-reel in the usual manner, and stretch an elastic cord, A, or other flexible material, as shown in the dotted line, Figure 1, parallel and lengthwise the exterior surface of the reel, and fasten it to springs B B, attached in any convenient manner to the bolting-chest.

Around the middle, or at each end of the reel, are ratchet-bands K K, which raise the cord, and allow it to snap or whip each side of the bolting-reel, one or more times as it revolves.

The cord at a a is provided with leather, or other suitable material, to prevent injury by friction; or by placing similar projections to K K upon the shaft, and using a cam-shaped lever, the cord may be raised and let fall, and the same effect produced.

We are aware that projections similar to K K have been used for the purpose of jarring the reel; therefore we do not claim only the extra bands for the purpose herein described.

Around the reel, in one or more places, are flexible bands H H, to prevent the snapping or whipping of the cord from injuring the bolting-cloth.

On each end of the cord, after passing through the springs, may be fastened weights sufficient to draw the cord out of the bolting-chest, and prevent it from injuring the cloth, if at any time it should be broken.

What we claim as our invention, and desire to secure by Letters Patent, is

In combination with a bolting-reel, having ratchet-bands K K, placed on each end, the arrangement of the cord A, extending lengthwise the exterior of the bolt, and fastened to springs B B, substantially in the manner herein set forth.

RUFUS S. MITCHELL.
GEORGE Z. KESSINGER.
